W. W. HELLE,

SHADE ROLLER.

APPLICATION FILED JUNE 29, 1916.

1,238,014.

Patented Aug. 21, 1917.

UNITED STATES PATENT OFFICE.

WARREN W. HELLE, OF HINSDALE, ILLINOIS, ASSIGNOR TO STARITE MANUFACTURING COMPANY, OF CHICAGO, ILLINOIS, A CORPORATION OF ILLINOIS.

SHADE-ROLLER.

1,238,014.

Specification of Letters Patent. Patented Aug. 21, 1917.

Application filed June 29, 1916. Serial No. 106,598.

To all whom it may concern:

Be it known that I, WARREN W. HELLE, a citizen of the United States, residing at Hinsdale, in the county of DuPage and State 5 of Illinois, have invented new and useful Improvements in Shade-Rollers, of which the following is a full, clear, concise, and exact description, reference being had to the accompanying drawing, forming a part of 10 this specification.

My invention relates to shade rollers.

Among the objects of my invention is to provide a shade roller which shall be simple and durable in construction, reliable in operation and cheap to manufacture.

A further object is to provide a shade roller in which the majority of the parts are constructed of formed sheet metal.

In the drawings, in which I have shown 20 one embodiment of my invention—

Figure 1 is a front elevation of a shade and roller embodying my invention;

Fig. 2 is an enlarged front elevation of the shade roller and shade, parts being broken 25 away;

Fig. 3 is a section of the left hand end of the roller on the line 3—3 of Fig. 2;

Fig. 4 is a section of the right hand end of the roller on the line 3—3 of Fig. 2;

Fig. 5 is a transverse section on the line 30 5—5 of Fig. 3;

Fig. 6 is a plan view of the bearing cap;

Fig. 7 is a transverse section on the line 7—7 of Fig. 4;

Fig. 8 is a section on the line 8—8 of 35 Fig. 4; and

Fig. 9 is a section on the line 9—9 of Fig. 2, showing the pawl.

Referring now to the drawings in detail, 40 my invention is shown in connection with a shade roller 10, one end of which is rotatably mounted in a bearing cap 11 detachably engaging a bracket 12 which is secured to any suitable support as 13, and 45 the other end of which roller is rotatably mounted in a combined bearing cap and bracket 14 which is secured to any suitable support as 15. A shade 16 is attached to the roller between the bearing caps.

50 The roller 10 comprises two telescopic tube sections 17 and 18, one of said sections being provided with a tongue 19 which engages beneath a keeper or strap 20 struck up from the material of the other tube section. These tube sections may be formed of

sheet material rolled so as to leave slots 21 and 22 between adjacent edges through which the shade 16 extends. A rod 23 is secured in a loop 24 in the upper edge of the shade. This rod 23 is so large that it will 60 prevent the edge of the shade from being pulled out through the slots 21 and 22. The bearing cap 11 may also be formed of sheet material and is provided with a flange 25 for guiding the edge of the shade. A T- 65 shaped lug 26 is secured to the cap in any suitable manner and engages a slot 27 in the bracket 12 to hold the cap in position and prevent its rotation. A spring 28 is provided for rewinding the shade after it has 70 been pulled down, one end of which spring engages beneath keepers or straps 29 which may be struck up from the material of the cap 11. A rod 30 is provided to hold this spring in its proper position and a pin 31 75 is inserted in one end of the rod and the end of the spring is secured to this pin by being inserted through an opening 32 in the pin. The end of the rod 30 may be provided with a ferrule 33. This pin 31 extends through 80 an opening 34 in a tongue 35 struck up from the material of the tube 17 and is held in position by means of a split pin 36 inserted through an opening in the pin 31. An opening 37 may be provided in the tube 17 to 85 permit access to the split pin 36. The combined cap and bracket 14 may also be formed of sheet material shaped to provide a flange portion 38 for guiding the edge of the shade and a base portion 39 by which it is secured 90 to the support 15.

For holding the shade in the position in which it has been withdrawn against the action of the spring 28 a pawl 40 is provided pivoted at 41 to the bearing cap 11 95 and extending through an opening 42 in the bearing cap 11 into engagement with the recess 42^a in the tube section 17. A keeper 43 may be struck up from the bearing cap to prevent lateral play of the pawl and the 100 pivotal movement of the pawl may be limited by means of a lug 44 struck up therefrom which operates in an opening 45 in the flange 25 of the bearing cap. To secure the shade to the roller one end of the rod 105 23 is brought to a position ready to be inserted within the tube sections and the edge of the shade 16 is placed between the edges of the slot 22. The shade and rod are then moved lengthwise of the roller until the rod 110

23 is entirely within the roller. The end of the tube section 18 is then inserted in the bearing cap 14, the cap 11 is slipped over the end of the tube section 17 and the lug 5 26 is placed in position in the slot 27 of the bracket 12. When the shade is pulled down the pawl 40 drops into and rides out of the opening 42^a on each revolution of the shade roller, and when the shade has been drawn 10 down as far as desired the pawl drops into the recess 42^a and holds it against the action of the spring 28. When it is desired to roll the shade up the shade is pulled down a short distance and allowed to be drawn up- 15 ward quickly by means of the spring 28, the roller being rotated so rapidly that the pawl 40 does not have time to drop down into the recess 42^a sufficiently to check the movement of the roller.

Copies of this patent may be obtained for five cents each, by addressing the "Commissioner of Patents, Washington, D. C."

Having thus described my invention what 20 I claim as new and desire to secure by Letters Patent is:—

In a device of the character described, a shade roller comprising a sheet of metal bent into the form of a hollow cylinder, the 25 edges of said sheet being adjacent each other but spaced apart, forming a slot the entire length of the cylinder, said cylinder being of uniform diameter and entirely open at its end, a flexible sheet, having a retaining 30 member secured thereto inside of said cylinder too large to slip out through said slot, and a bearing member having an annular portion for engaging the end of said hollow cylinder to form a bearing therefor. 35

In witness whereof, I have hereunto subscribed my name.

WARREN W. HELLE.
